DOFFER COMB DRIVE

Oscar C. Kay and Vernon Rowe, Chesnee, S. C.

Application February 25, 1946, Serial No. 649,918

3 Claims. (Cl. 19—106)

1

This invention relates to improvements in doffer comb oscillating mechanism of carding machines, and consists of the construction, combinations and arrangements hereinafter explained.

In a carding machine there is a rotating doffing cylinder for stripping the fibers from the main cylinder of the carding machine and an oscillating comb is provided for stripping these fibers from the doffing cylinder in the form of a web which is passed through a trumpet, formed into a sliver, and then through a suitable coiling mechanism and deposited into a can. This comb oscillates in a set location in the carding machine and the doffing cylinder rotates past the comb. The average comb makes about eight hundred oscillations per minute and in ordinary comb boxes heretofore employed there is excessive wear and as these boxes are filled with oil, a great amount of oil is consumed, the oil leaks out and does damage to the fibers and requires frequent cleaning, and as the wear increases in the comb box, it creates a vibration in the comb shaft. This vibration causes an uneven stroke of the comb and, consequently, impairs the efficiency of the comb in stripping the fibers off the doffing cylinder. This uneven running of the comb shaft also creates sufficient vibration to cause a flipping motion in the drive belt which will shorten the life of the drive belt.

It is an object of this invention to provide improved means for oscillating a comb shaft in a carding machine wherein a crank is placed on the comb shaft and this is connected by a connecting rod to a driven wheel and the point of connection of the crank to the connecting rod is adjustable and also the point of connection of the connecting rod to the wheel is adjustable to vary the stroke of the doffer comb as desired.

It is therefore an object of this invention to provide an oscillating mechanism for a doffer comb which will last much longer than the present comb box and by which the stroke of the doffer comb can be adjusted to suit various conditions.

It is another object of this invention to provide an oscillating mechanism for a doffer comb which eliminates the use of a box filled with oil, thus saving much oil, eliminating rapid wear of the parts, and providing a simple and efficient mechanism for accomplishing oscillation of the doffer comb shaft.

Some of the objects of the invention having been stated, other objects will appear as the de- 55

2

scription proceeds when taken in connection with the accompanying drawings, in which:

Figure 1 is an elevation of the exit end of a carding machine and showing our invention applied thereto;

Figure 2 is an isometric view of the adjustable member mounted on the driving wheel and connectable to the connecting rod for imparting oscillation to the doffer comb shaft;

Figure 3 is an enlarged vertical sectional view taken substantially along the line 3—3 in Figure 1;

Figure 4 is a sectional view taken substantially along the line 4—4 in Figure 1;

Figure 5 is a top plan view looking down on top of Figure 1;

Figure 6 is a vertical sectional view taken substantially along the line 6—6 in Figure 1;

Figure 7 is a top plan view of the lower portion 20 of Figure 5 and showing the same on an enlarged scale.

Referring more specifically to the drawings, the numerals 10 and 11 indicate the side frames of a carding machine which has a doffing cylinder 12 usually covered by a hood 13 and rotatably mounted on a shaft 14 and driven in a suitable manner to rotate along with shaft 14. This doffing cylinder has a plurality of conventional teeth 15 thereon which remove the fibers from the main cylinder of the carding machine. The carding machine also has a trumpet 16 through which the sliver 17 is passed and it is then passed between rollers 18 and 19 and up to a suitable coiling mechanism 20 and deposited into a conventional can 21.

All of this mechanism is conventional as well as a conventional rotary shaft 23 driven by a suitable V-belt 24 and having a V-pulley 25 thereon on which is mounted a V-belt 26 for driving a comb to be presently described. On top of frames 10 and 11 we mount gooseneck members comprising a horizontal portion 30 which is bolted to the top of frames 10 and 11. Each portion 30 has an uprising portion 31 and an elevated horizontal portion 32. Each of the portions 32 has a horizontally disposed hole therethrough in which is mounted the reduced ends 33 and 34 of a comb shaft 35. This comb shaft 35 has a plurality of arms 36 thereon and on the outer end of same is fixedly secured a doffer comb 37.

The reduced portion 34 of shaft 35 nearest the observer in Figures 1 and 2 has secured thereon by means of a split bearing 40 a lever 41 having a plurality of holes 42 therein in any one of which

is adapted to be mounted a shouldered stud bolt 43 on which is mounted a roller bearing 44 which is surrounded by an end portion 45 of a connecting rod 46. The other end of the connecting rod 46 has an annular portion 47 having a similar roller bearing therein, mounted on a similar stud bolt 48 which is threadably secured in a bracket 49 in the same manner in which stud bolt 43 is secured in lever 41. This stud bolt is internally threaded to receive a bolt 50 to confine that end of the connecting rod on the bolt 48.

The bracket 49 has a pin 52 extending inwardly therefrom which is adapted to fit into a hole 53 in a pulley 54 on which V-belt 28 is mounted. The bracket 49 has an arcuate slot 55 therein whose center is the pin 52 and slidably penetrating this slot is a bolt 56 which is threadably secured in a threaded hole 59 in the pulley 54. The pulley 54 is rotatably mounted on a stud bolt 57 threadably mounted in the upstanding portion 31 of the nearest gooseneck member to the observer in Figures 1 and 2. Mounted on this bolt 57 is a roller bearing 58, and on this roller bearing 58 is mounted the pulley 54.

It is thus seen that coarse adjustment of the length of the stroke of the doffer comb 37 can be obtained by placing bolt 43 in any one of the holes 42 in lever 41 while minute adjustment of the length of stroke can be accomplished by loosening bolt 56, slightly moving bracket 49 on its pivot pin 52, thus giving the desired length of stroke with one or two adjustments.

It is thus seen that we have provided means for oscillating a doffer comb in a carding machine in which a gear box filled with oil is eliminated and where the parts are easily accessible for adjustment and said parts are sturdy in construction and not liable to wear out easily, and accomplishing the desired result, and eliminating all of the defects of the old style comb box heretofore used for imparting oscillatory motion to the doffer comb.

In the drawings and specification there has been set forth a preferred embodiment of the invention, and although specific terms are employed, they are used in a generic and descriptive sense only, and not for purposes of limitation, the scope of the invention being defined in the claims.

We claim:

1. A carding machine having an oscillatable comb shaft provided with a plurality of arms extending therefrom and having a comb mounted on the outer ends of the arms for engagement with a doffer cylinder of the carding machine for removing a web of fiber therefrom, a bearing mounted near each end of said doffer shaft and in which the doffer shaft is mounted for oscillation, one end of the doffer shaft extending outwardly beyond its bearing, a crank arm mounted on the extending end of the doffer shaft, a connecting rod adjustably connected to the free end of the crank arm mounted on said doffer shaft, a rotatable pulley mounted for rotation on the bearing bracket which supports one end of the doffer shaft, means driven by the carding machine for imparting rotation to the pulley, an adjustable bracket pivotally mounted on the pulley and having a pin extending therefrom on which the other end of said connecting rod is pivotally

mounted, said bracket having an arcuate slot therein and a screw mounted in said pulley and penetrating said slot for adjusting the position of said bracket with relation to said pulley thereby to regulate the length of stroke of the oscillating doffer comb.

2. In a carding machine having a doffer cylinder and a doffer comb, a plurality of arms secured to the doffer comb, a doffer shaft secured to the other end of said arms, a bearing bracket mounted on each side of the carding machine and in which said doffer shaft is mounted for oscillation, one end of the doffer shaft extending outwardly from its associated bearing bracket, a lever having one end mounted on the extending end of the doffer shaft, a connecting rod adjustably connected to the free end of said lever, a bearing secured to an uprising portion of said bearing bracket associated with the extending end of the doffer shaft, a pulley mounted on said bearing, means driven by the machine for imparting rotation to the pulley, a bracket mounted on the outer face of said pulley and having a pin extending therefrom on which the other end of said connecting rod is pivotally mounted, said pulley having an eccentrically disposed hole therein and a pivot pin on said bracket oscillatably penetrating said hole, said bracket having an arcuate slot therein, whose center is said pivot pin, a screw threadably mounted in the pulley and extending through said slot whereby the bracket can be moved on its pivot and the screw driven home in said slot to hold the bracket in adjusted position thereby to regulate the length of swinging movement imparted to said lever connected to the extending end of the doffer shaft and thus regulating the length of reciprocatory movement imparted to the doffer comb.

3. In a carding machine having a doffer shaft with a doffer comb mounted thereon, a pair of bearing brackets extending upwardly from the opposed sides of the carding machine, said doffer shaft having extensions thereon rotatably mounted in said brackets, one of said extensions projecting outwardly a substantial distance beyond the outside of its associated bracket, a lever having one end mounted on the extending end of said doffer shaft, a wheel rotatably mounted on said bearing bracket associated with the extended end of said doffer shaft, means driven by the machine for driving the wheel, a bracket pivotally mounted on the exterior of said wheel and having an arcuate slot therein whose center is the place where the bracket is pivotally mounted on the exterior surface of said wheel, a bolt threadably mounted in the exterior surface of said wheel and penetrating said slot whereby the position of the bracket can be adjusted relative to said wheel, said bracket having extending outwardly therefrom a bearing pin, a connecting rod having one end thereof mounted for oscillation on said bearing pin, the lever mounted on the doffer shaft having a plurality of holes in its outer end, and means for oscillatably connecting the other end of said connecting rod to the outer end of said lever mounted on the extended end of the doffer shaft.
